UNITED STATES PATENT OFFICE.

EDWARD B. WESTON, OF DAYTON, OHIO.

PAPER-ROLL HOLDER AND CUTTER.

SPECIFICATION forming part of Letters Patent No. 415,233, dated November 19, 1889.

Application filed January 21, 1889. Serial No. 297,039. (No model.)

To all whom it may concern:

Be it known that I, EDWARD B. WESTON, a citizen of the United States, residing at Dayton, in the county of Montgomery and State of Ohio, have invented certain new and useful Improvements in Paper-Roll Holders and Cutters; and I do hereby declare that the following is a full, clear, and exact description of the invention, which will enable others skilled in the art to which it appertains to make and use the same, reference being had to the accompanying drawings, and to the letters and figures of reference marked thereon, which form a part of this specification.

15 My invention relates to improvements in paper-roll holders and cutters, the several features of which will be fully hereinafter set forth.

The general features of my invention resemble machines in use for the purpose, and the objects I have in view are the holding the paper of the roll by a rim of the knife held down by means of a weighted lever, and to support the edges of the paper between the 25 knife and pins on both sides, so that the paper may be readily grasped by the fingers. I attain these objects by the mechanism illustrated in the accompanying drawings, in which—

30 Figure 1 is a rear elevation of the machine. Fig. 2 is a view of the side of the same. Fig. 3 is a transverse section of the knife and contiguous parts on line α , Fig. 1.

Like letters designate like parts throughout the several views.

A is the base of the frame, and B the top.

H II are uprights which unite the base and top, and are secured by screws entering the flanges of said uprights.

40 O is a bearing in the side of the uprights for the support of the pinions of the shaft on which the roll of paper is suspended. Near the top of the uprights are pivoted the curved arms D, and to the lower ends of which is attached the knife C, by a screw entering through a lug of said arm. Below the journals of the roll-shaft in the center of the up-

rights are pivoted the weighted levers F, and these are united to said curved arms by the rods E. To the curved arms are attached the 50 pins G, which project inwardly beneath the rim of the knife.

The knife C is provided with a wide rim, which is nearly at a right angle to the body, and is shown in cross-section at Fig. 3. 55

The circular dotted line 1 shows the periphery of a full roll of paper, and the inner line 2 the roll reduced. The end 3 of the paper (likewise in dotted line) passes from under the rim of the knife over the pins G, and 60 the paper is cut off by drawing it upward and across the edge of the knife, and thus sheet after sheet is cut off of any desirable length as it is drawn from the roll. The weighted lever holds continuously the rim of the knife 65 against the roll, and the pins hold up the edges, and as a consequence the center of the paper bends downward, so that it is readily grasped beneath the knife by the fingers.

Having fully described my invention, what I 70 claim, and desire to secure by Letters Patent, is—

1. In a paper-roll holder and cutter, the combination of the frame with roller journaled in the ends, weighted lever F, pivoted beneath 75 said journals, connection-rod E, and arms D, with flanged knife C attached, said knife having its flange so held as to bear against the roll and the cutting-edge of the same held a distance therefrom, substantially as and for 80 the purpose set forth.

2. The combination of the curved arms D, pivoted to the frame, and with the flanged knife C attached, and pins G on said arms beneath the flange or rim of said knife to elevate the edges of a roll of paper, substantially 85 as set forth.

In testimony that I claim the foregoing as my own I affix my signature in presence of two witnesses.

EDWARD B. WESTON.
